HOOD CONTROL FOR MOTOR CARS

Arthur Claud Mantle, Trumbull, Conn., assignor
to The Bassick Company, Bridgeport, Conn., a
corporation of Connecticut

Application March 6, 1941, Serial No. 381,982

7 Claims. (Cl. 292—1)

This invention relates to hood controls for motor cars, and more particularly to latch mechanisms used with hoods of the lid type where a latch controlled from the dash is employed, there being in addition the usual safety catch or dog to maintain the hood under control after it has been released and opened to a slight degree. Upon suitably manipulating a member in the car interior, a shiftable latching member is released, and a spring comes into play to raise the hood to a limited degree. Then, after the safety catch has been released by the attendant, the hood can be swung to the fully opened position.

One of the objects of my invention is to provide an improved and simplified latching mechanism for use in devices of this class.

Another object is to furnish an improved spring mechanism for causing opening of the hood to a certain extent after the latch or detent has been released.

Another purpose of the invention is to provide an improved form of latching keeper for use in devices of this kind.

To these and other ends the invention consists in the novel features and combinations of parts to be hereinafter described and claimed.

In the accompanying drawings:

Fig. 1 is a side elevation, partly broken away and partly in section, of a hood control device embodying my improvements, showing the hood in the fully closed position;

Fig. 2 is a plan view of certain parts shown in Fig. 1, partly in section along line 2—2 of Fig. 1;

Fig. 3 is an enlarged section on line 3—3 of Fig. 1;

Fig. 3A is a plan view of a portion of the upper plate showing the fastening means for the keeper;

Fig. 4 is a bottom plan view of the lower plate and its associated mechanism;

Fig. 5 is an enlarged transverse section through the upper and lower plates showing the latch mechanism in the fully closed position;

Fig. 5A is a bottom plan view of certain parts shown in Fig. 5;

Fig. 6 is a section on line 6—6 of Fig. 5;

Fig. 7 is a side elevation partly in section, showing the latch mechanism of Fig. 5 fully released and the hood pushed upwardly as far as permitted by the controlling spring;

Fig. 8 is a sectional view similar to Fig. 5, showing a modification of the device, and

Fig. 9 is a section on line 9—9 of Fig. 8.

In the forms of my device selected for illustration, the movable part, which I refer to as the hood, is of the lid type, opening from the front

end of the car, and the hood carries a transverse plate, termed the upper plate, provided with a safety catch or dog which cooperates with the front portion of a lower plate held fixedly in position within the casing portion adjacent the radiator of the car. Between the upper liftable plate and the lower fixed plate there is also provided a latching mechanism comprising a shiftable detent part controlled from the interior of the car, this detent part cooperating with a latching member or keeper carried by the upper plate; and spring mechanism is provided for lifting the hood to a limited degree immediately upon release of the detent.

In the drawings, the hood proper is shown at 10, the lower casing part of the hood enclosure, at 11, the upper plate at 12, and the lower plate at 13. The safety catch or dog carried by the upper plate is shown at 14, and this cooperates in the usual manner with a notched portion 15 in the front edge portion of the lower plate, and this safety catch is controlled in the usual manner by a suitable spring, for example, a spring such as indicated at 16. The shiftable detent, previously referred to, is shown at 17, and this may be controlled from the dash 18 of the vehicle by means such as a knob 19 connected to the rear end of a cable 20. The keeper previously referred to, is indicated at 21 and is of new form and arrangement, as hereinafter more particularly described, and the spring mechanism 22, which urges the hood upwardly, upon its release, is also of novel construction and arrangement, as hereinafter more particularly described.

The detent member 17 may be of a type previously employed, in other words, in the form of a lever pivoted to the lower plate at 23 and having a free extremity 24, to which the end of cable 20 is operably connected. This lever cooperates with keeper 21 in the manner hereinafter described. In the form shown, the pivoted end portion of the detent lever is disposed beneath plate 13 and pivoted to the plate by a suitable rivet member having a head 25. Midway of its ends the lever passes through an arcuate guide slot 26 in the plate to the upper side of the plate, and at the upper side of the plate is provided with a down-turned lug 27 operating in an arcuate slot 28. The lug 27 has connected thereto a helical spring 29, the other end of which is connected to the plate at 30, the action of this spring 29 being normally to hold lever 17 in the position shown in full lines in Fig. 2, where it has holding relation with respect to keeper 21. Upon pulling the cable 20, the lever is shifted to release the bolt.

From Fig. 2 it will be observed that the notch 15 for the safety catch is disposed slightly to one side of the longitudinal axis of plate 13, and that keeper 21 is disposed slightly to the other side of such axis so as to cooperate with lever 17 in a region of the lever which is relatively close to the lever pivot. The keeper 21 is carried by the upper plate but adapted to be projected through an opening 31 into cooperation with the lever 17, and also into cooperation with the spring mechanism 22.

The keeper 21 is of novel form having a relatively thin and flat head 32 with a shoulder 33 at one side adapted to engage the under surface of the detent lever. The lower part of the keeper head is made wider so as to present at one side this upwardly facing shoulder 33. Above this shoulder the width of the head is reduced, as shown at 34, and this portion is formed integral with a shank portion 35, which extends upwardly through the upper plate 12 and is attached thereto in a suitable manner.

In the preferred form, the shank 35 is threaded and passes upwardly through an opening 36 in plate 12 and into an interiorly threaded member 37 in the form of a plate having end extensions 38 by means of which it is spot welded to plate 12 in a recessed portion 39 at the upper face of the latter. By this construction the part 37 acts as a fixed threaded socket into which the shank of the keeper can be screwed. For firmly holding the keeper in the vertical position to which it is adjusted, a lock nut 40 is used at the lower face of plate 12.

In order to facilitate the entrance of the keeper head into the opening 31 in the lower plate the opening is preferably formed in part to present the profile shown in Fig. 3, the material of plate 13 being bent to provide guiding and centering portions 41 at the respective sides of the slot-like opening. These portions 41 extend inwardly and downwardly to engage and guide the keeper as it moves to the locking position, and preferably, as shown in Fig. 3, parts of the portions 41 are disposed above the plane of plate 13, while other parts are below said plane. Immediately back of the portions 41 the opening 31 has a plain slot-like portion 42 immediately beneath which a latching portion 43 of the lever 17 is disposed.

In my improved device, the spring 22, previously mentioned, acts directly upon the head of the keeper so as to urge the same and the parts connected thereto in an upward direction. I prefer to form the spring 22 of suitable wire and to provide it with an intermediate bail portion which engages the keeper head. In the form shown in Figs. 1 to 7, inclusive, the spring comprises a main coil portion 44 carried by the lower plate and having a bail portion 45, the end 46 of which extends across and is adapted to engage the lower edge of the keeper head in the manner shown in Fig. 5. When the hood is raised the bail portion of the spring engages lips 41^a at the lower edges of the portions 41, but when the hood is closed the bail portion of the spring is forced to the position of Fig. 5. Preferably the extremities of the spring wire, which are indicated at 47, are alongside of each other in a holding depression 48 in plate 13, and from each extremity the spring wire passes forwardly to become a part of coil portion 44 at the middle portion of the coil, and from the middle portion the wire is extended to the ends of the coil, and from the ends of the coil the wire is projected

outwardly to form the bail portion which acts on the keeper head. As shown in Figs. 2 and 5, the coil of the spring is preferably arranged forwardly, and the bail portion at the rear, but this arrangement is not essential.

In the particular form shown, the coil portion 44 of the spring is located adjacent the forward edge of the lower plate 13, and is held in place, when the keeper is inactive, by the engagement of the coil portion with a down-turned lip or flange 13^a on the plate, by the engagement of the spring extremities in the seat or depression 48, and by the engagement of the bail portion of the spring with the lower edges of the keeper opening, as above described. From the coil the free extremities are directed upwardly and rearwardly to engage their holding socket, while the bail-forming arms or portions of the spring are directed downwardly from the coil and then upwardly, as shown in Fig. 7.

It is thought that the operation of the device will be manifest from the previous description. Assuming that the hood member 10 is in the closed position shown in Fig. 1, the same may be released by the driver of the car from the driver's seat by manipulating the cable knob to shift the detent lever against the action of the spring 29. As this lever is shifted rearwardly, the latching portion 43 thereof is moved rearwardly out of engagement with the shoulder on the keeper head, as indicated by the dotted lines in Fig. 5. The bail portion of the spring will then be able to act on the keeper head to push the keeper upwardly, carrying with it the upper plate and the hood member attached thereto. The spring 22 will move the keeper and its attached parts to the position shown in Fig. 7, where the bail portion of the spring comes in contact with the under part of the lower plate. The lower edge of the keeper rests against the middle part of the bail, which middle part preferably has downwardly converging and centering portions, as indicated in Fig. 3.

In the position of Fig. 7, the hood member will be open to a substantial extent, but will not be open to the full extent permitted by the safety catch 14. It will be possible for the attendant to insert his hand into the opening, and, by engaging a pad portion 14^a at the upper end of the safety catch, move the safety catch on its pivot 14^b to a position in which its lower hooked extremity 14^c is swung out of cooperative engagement with the front edge portion of the lower plate. The hood can then be pushed upwardly for the complete opening of the same.

When the hood is closed again, the bolt head moves down into its slot in the lower plate and a curved edge portion 32^a thereof engages and pushes back the detent lever so that the latter snaps over the shoulder on the bolt head to lock it. As the bolt is forced by downward thrust on the hood toward the locking position, it engages and energizes the spring 22. It will be evident that in the latching position the keeper will be effective to increase the firmness of the seating and interlock of the spring with the lower plate.

In the form shown in Figs. 8 and 9, the keeper shank 35 is held in position relatively to the upper plate by an upper nut 49 and a lower nut 50. There is a difference also in respect to the form of the keeper-engaging spring 22^a. In this case the extremities 51 of the spring wire are at the sides of the spring in spaced relationship to each other, and are held in place by clips 52 riveted over at the upper surface of flange 13^a, as indi-

cated at 53. In this case the portions 54 which form the bail project from the inner parts of coils 55, which are laterally spaced from each other.

By the construction described, a very simple and effective latch mechanism between the upper and lower members of the hood casing or enclosure is provided, which can be easily controlled from the interior of the car, and is durable and will withstand hard usage without getting out of order. As the keeper head is moved through the lower plate to the latching position, it is properly guided so that the latching action will take effect without difficulty. The spring mechanism, by which the members of the hood enclosure are normally held separated to a certain extent, is very simple and effective in action after the spring has been installed. It will maintain its operative position without difficulty. It will also be noted that, with the parts arranged in the manner described, they will be conveniently accessible for repairs if after extended use repairs or replacements are necessary.

While I have shown two forms of my improved hood control device, it will be understood that the invention can be embodied in various other forms, and that various modifications and changes in the organization of parts and in the details may be made without departing from the principle of the invention or the scope of the claims.

What I claim is:

1. In a hood latch of the type comprising upper and lower plates of which the upper carries a depending rigid keeper with a flattened head having a narrow lower edge, said keeper in the latching position occupying a slot in the lower plate with the lower edge of the keeper head substantially below the plane of the lower plate, the lower plate being provided rearwardly of the keeper with detent means adapted to overlie the keeper head, a spring acting on the lower edge of the keeper head for urging the keeper in an upward direction, said spring being formed of wire and having a coil portion located forwardly of the keeper at the under surface of the lower plate and abutted against a projecting portion of said plate, said spring having a lower integral continuation from the coil portion extending across and engaging the lower edge of the keeper head, and said spring having integral rearwardly disposed anchoring portions extending from the coil portion above the bail portion interlocked with the plate to hold the spring in position in pressing relation to the keeper head.

2. In a hood latch comprising upper and lower plates of which the upper carries a depending rigid keeper with a flattened head having a narrow lower edge, said keeper in the latching position occupying a slot in the lower plate with the lower edge of the keeper head substantially below the plane of the lower plate, the lower plate being provided with detent means adapted to overlie the keeper head, a spring located at the under portion of the lower plate and acting on the lower edge of the keeper head for urging the keeper in an upward direction, said spring and the lower plate having interengaging means whereby the spring is interlocked with said plate and seated thereagainst with the keeper in the latching position increasing the firmness of the seating.

3. In a hood latch comprising upper and lower plates of which the upper carries a depending

rigid keeper with a flattened head having a narrow lower edge, said keeper in the latching position occupying a slot in the lower plate with the lower edge of the keeper head substantially below the plane of the lower plate, the lower plate being provided rearwardly of the keeper with detent means adapted to overlie the keeper head and being provided forwardly of the keeper slot with a downward projection, a spring acting on the lower edge of the keeper head for urging the keeper in an upward direction and having a coil abutted against said projection and an anchoring portion interlocked with a portion of the plate so that the spring is held in operative position under tension.

4. In a hood latch comprising upper and lower plates of which the upper carries a depending rigid keeper with a flattened head having a narrow lower edge, the lower plate being provided with movable detent means adapted to overlie the keeper head, a spring having a bail portion extending across and acting on the lower edge of the keeper head for urging the keeper in an upward direction, said spring and the lower plate having interengaging means including a transverse coil portion and an anchoring extension on the spring whereby the spring is interlocked with said plate and seated thereagainst with the keeper in the latching position increasing the firmness of the seating.

5. A hood latch of the kind set forth in claim 4 in which the coil portion of the spring is seated in an angular portion of the plate, the bail portion extending from the coil portion at a lower level and the anchoring extension extending from the coil at an upper level and being engaged with a socket formed in the plate.

6. In a hood latch comprising upper and lower plates of which the upper carries a depending rigid keeper with a flattened head having a narrow lower edge, said keeper in the latching position occupying a slot in the lower plate with the lower edge of the keeper head substantially below the plane of the lower plate, the plate having downturned lips at the respective sides of the slot and having a movable detent member mounted thereon adapted to overlie the keeper head, a spring located at the under portion of the lower plate and having a transverse bail portion acting on the lower edge of the keeper head for urging the keeper in an upward direction, which bail portion when the keeper is lifted out of the lower plate lies against and across the lips of said slot, and means for interlocking the spring with the lower plate so that it is held under tension.

7. In a hood latch comprising upper and lower plates of which the upper carries a depending rigid keeper, the lower plate having mounted thereon movable detent means adapted to overlie the keeper to latch the hood, a spring located at the under portion of the lower plate and acting on the keeper from beneath for urging the keeper and upper plate in an upward direction, said spring and the lower plate having interengaging means whereby the spring is interlocked with said plate and seated thereagainst with the keeper in the latching position increasing the firmness of the seating.
